UNITED STATES PATENT OFFICE.

JOHN SAMUEL SUNDERLAND, OF LONDON, ENGLAND.

APPARATUS ACTUATED BY CLOCK-MOVEMENTS FOR STARTING OR STOPPING MACHINERY.

SPECIFICATION forming part of Letters Patent No. 702,682, dated June 17, 1902.

Application filed February 12, 1902. Serial No. 93,665. (No model.)

To all whom it may concern:

Be it known that I, JOHN SAMUEL SUNDERLAND, electrotyper, a subject of the King of Great Britain, residing at 37 Aberdeen road, 5 Highbury, London, England, have invented certain new and useful Improvements in Apparatus Actuated by Clock-Movements for Starting or Stopping Machinery, of which the following is a specification.

10 This invention relates to a device actuated by a clock-movement for starting or stopping machinery at any required time.

According to my invention I employ a clock-movement of any well-known and appropriate construction which can be arranged to release or operate a spring, lever, weight, or other device at any predetermined time and to thereby, through the intervention of cam, lever, or other suitable mechanism, start or 20 stop any machinery employed for electrical, chemical, hydraulic, mining, milling, electro-plating, or other purposes.

In order that my invention may be more clearly understood and readily carried into effect, I will proceed to describe the same more fully in connection with the accompanying drawings, in which—

Figure 1 shows the apparatus before the release of the starting or stopping device, and 30 Fig. 2 shows the apparatus after the release of the said device. Fig. 3 is a front elevation, and Fig. 4 is a plan, both on an enlarged scale, of the clock-movement with the dial removed. Fig. 5 is a diagram showing the 35 device adapted to stop a power washing-machine at a prearranged time.

a is the face of a clock, provided with a spring *b* and with a supplementary dial *c* and indicator or hand *d* for determining at what 40 hour the spring *b* shall be released in the same manner as in an ordinary well-known alarm-clock.

e is a pawl pivoted to the clock-case and having an arm *f*, which bears upon the spring *b*.

45 *g* is a weak spring for holding the arm *f* in contact with the spring *b*. The tooth *h* of the pawl *e* is adapted when the spring *b* is wound up to engage with a hook or tooth *i* on an arm *j*, carried by a rod *k*, adapted to 50 slide longitudinally in guides *l l*.

m is a spring which tends to move the rod *k* away from the pawl *e*.

Referring to Figs. 3 and 4, the spring *b* has one end fixed to the clock case or frame and the other connected to a spindle *b'*, which 55 also carries a handle *b²* for winding up said spring. The spindle *b'* also carries a ratchet-wheel *b³*, connected by a spring-pawl *b⁴* to a toothed wheel *o*, loosely mounted on the spindle *b'* and connected by a gear-train *p q r* to 60 an escapement-wheel *s*. The escapement-wheel *s* is normally held stationary by a tooth or pawl *t*, carried by a rocking shaft *u*, which also carries an arm *v*. *w* is a spring fixed at one end to the frame of the clock and having 65 its opposite end bent and adapted to be moved into and out of the path of the arm *v*. The hooked end of the spring *w* also bears upon the hub of a toothed wheel *x*, mounted loosely upon the spindle *d'* of the indicator *d*, said spring 70 tending to hold an incline *x'* on the wheel *x* in contact with a pin *d²*, carried by the spindle *d'*. *d³* is a handle for turning the indicator *x* and simultaneously moving the pin *d²* to the required point on the incline *x'* to 75 insure that the escapement-wheel *s* is released and the spring *b* permitted to expand at the proper time. The toothed wheel *x* is connected by gear-wheels *x² x³ x⁴* to the clock-movement operated, as is well understood, 80 by the mainspring *y* and an escapement *z*.

When the spring *b* is wound up and the indicator *d* set to the required time, the free end of the spring *w* is held in the path of the arm *v* by the pin *d²*, bearing upon the incline 85 *x'*. The clock-movement gradually rotates the wheel *x*, while the pin *d²* remains stationary until a shoulder *x⁵*, in which said incline terminates, reaches said pin. The spring *w* is then permitted to move the wheel 90 *x* along the spindle *d'* until the pin *d²* reaches the lowest point of the incline *x'*. This movement of the spring *w* is sufficient to release the arm *v* and escapement-wheel *s*, thereby permitting the spring *b* to expand and operate the pawl *e*. When the spindle *d'* is rotated to again set the indicator *d*, the pin *d²* by moving along the incline *x'* again moves spring *w* into the path of the arm *v*.

As shown in Fig. 1, the spring *b* is wound 100 up and the hook *i* is in engagement with the tooth *h*, thereby holding the rod *k* toward the left against the resistance of the spring *m*.

In Fig. 2 the spring *b* has just been released

and the spring *b* by expanding has raised the tooth *h* of the pawl *e* out of engagement with the hook *i* on the arm *j*, thereby releasing the rod *k* and permitting the spring *m* to move 5 said rod toward the right for starting or for stopping any required apparatus. The rod *k* may be connected in any appropriate manner to the starting or stopping device of the required apparatus.

10 To reset the starting or stopping apparatus, the indicator *d* is moved so as to point to the required starting or stopping time and the spring *b* is wound up, as is well understood. The rod *k* is then moved by the knob or fin- 15 ger-piece *n* and against the resistance of the spring *m* until the hook *i* engages with the tooth *h*.

Referring to Fig. 5, 1 is the washing-machine, adapted to be actuated by band-and- 20 pulley gear from a rotary shaft 2, driven from any suitable source of power. 3 is a fixed pulley on the shaft 2, and 4 is a pulley running loose upon said shaft. 5 and 6 are respectively fixed and loose pulleys upon a shaft 25 7, geared by toothed wheels 8 with the washing-machine 1. 9 is a rod adapted to slide in the direction of its length and supported in bearings 10 10. The rod 9 carries a loop 11, embracing the band 12, and is pivoted at 13 30 to an arm 14, pivoted at one end to a fixed point 15. The end of the rod *k* is connected to the arm 14.

As shown in Fig. 5, the hook *i* is engaged by the tooth *h* of the pawl *e*, and the spring *b* is wound up. When the clock-movement releases the spring *b*, as above described, the rod *k* is liberated and pushes the arm 14 and rod 9 in the direction of the arrow, thereby shifting the band 12 from the fixed pulleys 3 35 5 onto the loose pulleys 6 8, as shown in dotted line, and permitting the machine 1 to stop.

What I claim, and desire to secure by Letters Patent of the United States, is—

1. In a mechanical starting or stopping device, the combination with a clock-movement, 45 a spring, means for putting said spring under tension, means operated by the clock-movement for releasing said spring at a prearranged time, a starting or stopping rod, a spring arranged to act on said rod, and a spring 50 acting on said releasing means to normally hold the same in engagement with the rod.

2. In a mechanical starting or stopping device, the combination of a clock-movement, a spring, means for putting said spring under 55 tension, a pivoted member arranged to be engaged directly by the spring as it unwinds, a starting or stopping rod, a hooked arm carried thereby, interengaging means between said arm and pivoted member, and means acting on said member to normally hold said interengaging means in locked position.

3. In a mechanical starting and stopping device, the combination of a clock-movement, a spring, means for putting said spring under 65 tension, an escapement-wheel, a gear-train connecting said escapement-wheel with the spring, means for normally holding said escapement-wheel stationary, a pivoted pawl which bears upon the spring, a starting or 70 stopping rod, a spring which tends to move said rod away from the pawl, a hook carried by the rod and adapted to engage with the pawl when the spring is under tension and thereby hold the rod against the resistance of 75 its spring, and means operated by the clock-movement for releasing the escapement-wheel at a prearranged time substantially as described.

In testimony whereof I have hereunto set 80 my hand, in presence of two subscribing witnesses, this 28th day of January, 1902.

JOHN SAMUEL SUNDERLAND.
